edge of the lintel 36 is employed to control a coin diverter 41 to direct the operating coin into the money box 22 when a tablet has been dispensed, and to return the coin to the operator when the device is empty of tablets. A shelf 42 of segmental form is supported on vertical posts 43 above the face of the partition 29 and held thereto by screws 45 adjacent the position of the ridge 35 and hole 33 to allow a single row of packages or tablets 34 to move along the face of the partition 29 toward the discharge opening 33, and to prevent more than one tablet or package 34 from dropping through the discharge opening 33. Figure 5 shows the diverter 41 in position to return coins through the slot 47. The money box 22 has a dispensing chute or cup 46 formed interiorly for the dispensing of the tablets 34 when dropped into it through hole 33 and for returning the coin to the owner through slot 47 and cup 46 when the vender is empty, through the action of the diverter 41. The diverter 41 is actuated by the lintel node 40 when the vender is empty, so as to divert coins from the coin chute back to the customer when there are no tablets to deliver. The diverter 41 is hinged at 48 and ordinarily is positioned so the coins used to operate the vender will pass directly into the money box 22 when the tablet product is normally dispensed from the machine. A spring 50 preferably of flat form is held in the recess 49 of a coin tube 51 that contains the rectangular passage 52 for the coins to travel in and actuates the diverter 41 to return the coin when the machine is empty. The opening 56 is closed by a tilting door 57 tensioned by spring 58. The cap 20 and body 21 are provided with bosses 53 and 54 and held together by screws 55. The cap 20 is formed with a coin slot 59 that is not large enough of itself to permit the insertion of coins to operate the vender. However, a relatively small knob or head 60 revolves on top of the cap 20 in a recess 61 depressed in the latter to take it. The knob or head 60 has a stem 62 extended down from it into the housing through a bushing 63 that serves to keep it straight and prevent sidewise movement while at the same time serving as a bearing in which to rotate it. The knob or head has a rectangular slot 64 in its stem 62 and through its longitudinal axial area leading into the cap 20. At the entrance of the slot 64 the size is reduced, so it has to align with the slot 59 to provide sufficient length for the coin selected to pass into it, and thence through the axial area down into the coin tube of the vender. The slots 59 and 64 are normally located so the customer is not required to turn the knob to align them so he can insert the coin of the proper size. This alignment is accomplished through a spring 65 attached to a pin 66 positioned in the recess 61 of the cap 20 and the other end of the spring attached to a pin 67 positioned in the knob 60 and keeps the slots 59 and 64 in alignment. When the coin is inserted in the knob it falls down through the slot 64 and between one set of the radial fins 69 formed in the rotatable collar 70 which is attached to the magazine 71. However, when the coin reaches the magazine it is stopped by a slot 84 in the partition 72 at the top of coin tube 51 that is of smaller diameter than the coin used, and engages between one set of radial fins projecting vertically above the coin tube 51 and within the magazine and acts as a key to lock the knob stem and magazine together so the magazine can be rotated enough to dispense one

tablet or container and drop the coin into the money box. The rotation of the knob and magazine revolves the coin in its vertical position to and over the enlarged notches 73 in the partition 72 which is of the same diameter as radial fins 5 and slightly larger than coin used, and aligned with the enlarged passage 85 and rectangular passage 52 in the coin tube 51 and the largest passage, is large enough for the coin used. The magazine 71 is positioned and rotates on the coin tube 51 which is substantially parallel to the columns of the magazine, which are hollowed out to hold the tablets 34 in one position so they will slide down onto the partition 29 in proper sequence and in rotative movement as explained in previous patent referred to and also described herein. The tube 51 is arranged with a rectangular passage 52 for the coin to pass through on its way to the disposal chamber 32. A groove 75 in the wall of the magazine 71 allows the shelf 28 to slide therethrough as it is rotated and keep the tablets 34 from falling down indiscriminately into the cup 46 but not obstructing the dispensing of the tablets or units one at a time in the proper sequence. The money box 22 is attached to the partition 29 and held there by adjustable screws 78 which fit into slots 79 in breechlock fashion, and allow various adjustments to be made to tightly fit the money box 22 to the partition and other parts of the vender. The vender is then secured to the back bracket 23 by a lock 80 mounted in the bottom wall 81 of the money box 22 when operated by a key 83 in the usual manner causes the tongue 82 to engage in slot 27 in the back bracket 23 so the money box section or the vender cannot be removed from the wall except by unlatching the lock with a key and raising the vender so the screw 26 will be released from the slot 25 in the back bracket which has been attached to a wall or other support.

In the operation of the machine, the user if necessary turns the knob 60 until its vertical slot 64 is aligned with the angular slot 59 in the cap 20, so a coin or slug 68 of the proper size can be inserted. The slots contemplate the use through them of any item of predetermined form that may be employed for operating the vender, whether it be of conventional coin or slug form or not. The term "coin" is intended to include any item of this nature, without requiring further detailing thereof. The coin inserted passes through the passage 64 in the stem 62 vertically or on edge, until it wedges between the walls of this passage 64 and between the particular fins 69 immediately aligned therewith. Further turning of the knob will move the stem 62, the coin 68 and the fins 69. The fins 52 being integrally formed on the rotatable magazine 71 and locked for the moment with the stem 62 by the coin 68, are rotated when the knob 60 is turned. The coin 68 cannot pass through the tube passage in the magazine because it is obstructed by the face of the coin tube 51 which is stationary. However when the magazine, together with its tablets in the columns are revolved enough to bring the coin 68 in line with the passage 52 in the coin tube 51 and free of the obstructing surface of the face of the coin tube 51, it falls down unobstructed through the passage 59 and passes the diverter 41, into the money chamber 32. Since one of the columns with tablets therein is aligned with the cup 46 and its lowest tablet has been segregated by and under the shelf 42, so it 70 is over the open hole 33 in partition 29 during

5

the rotation of the magazine by the knob 60, it falls down through the cup 46 and lands against the door 57. The customer raises the door and removes the tablet.

Should no tablet be aligned with the hole 33 in this step of the dispensing, then the lintel mechanism comes into action under the tension of the spring 38 to move over the opening 33 and close it, while the node 40 of the lintel 36 moves away from the diverter 41 and allows the latter, under pressure of spring 50, to move and to change the course of the coin from the money box to the cup, where it can be taken out by the customer.

After the coin 68 is inserted in the slots 59 and 64 and fins 69 and rotates the magazine one space and coin is released to the coin tube, the knob revolves backwards to its starting point under the action of the spring and the device is ready for operation by the next customer, in the same manner as above described. The magazine is prevented from revolving backwards by a ratchet 76 mounted on the magazine or carrier and a spring or pawl 77 affixed to the stationary coin tube 51 respectively.

The money box 22 is removed periodically to take out the money and then be returned and locked in place. The tablets are stored in the magazine singly or in specified quantities as may be desirable or necessary and are termed units. The term unit being employed to include either single or plural tablets dispensable at a time for each single coin. The knob 60 is returnable to a definite location on the housing so its slot will automatically align with the slot of the housing. It assumes this position under the tension of a spring 65 fastened to the knob and housing cap as previously explained.

While but one general form of the invention is shown in the drawings and described in the specifications, it is not desired to limit this application for patent to this particular form, as it is appreciated that other forms of construction could be made that would use the same principles and come within the scope of the appended claims.

Having thus described the invention, what is claimed is:

1. A dispensing machine operable by coin manipulation, comprising in combination, a housing, a tablet magazine rotatable in said housing, said magazine being arranged to store a plurality of tablets disposed in individual units one above the other and in columns arcuately positioned within the magazine and deliverable in single units at the bottom, a shelf extending into the magazine on which the tablets can slidably rotate and arranged to allow each column of tablets to align consecutively therewith and release a unit therefrom individually at a time for its removal from the magazine, a coin tube within the magazine for guiding said coin therethrough, a knob rotatable on the housing and having a lateral slot for the insertion of the coin therein and an axial passage through the knob communicating with said slot for guiding the coin to the tube and to the magazine and bridging and keying the knob and magazine together whereby the further rotation of the knob will produce corresponding rotation in the magazine and bring each column selectively to said position of release, said magazine being arranged to align itself with said tube in said position and drop the coin from its bridging position into the tube, a coin box in the housing adapted to receive the coin from said

6

tube, a delivery cup in the housing alignable also with the column in its releasing position for receiving the unit dispensed therefrom simultaneously with the dropping of the coin, and means

5 for returning the knob to its normal position on the housing ready for the next coin to be inserted, without moving said magazine during said return, and a plate in the housing on which the magazine rests including an opening therein for 10 the unit to drop through, means operating in the housing adjacent said shelf for leaving the opening through which the unit may fall to the cup open as long as there are tablet units in the magazine to press it open.

15 2. A dispensing machine operable by coin manipulation, comprising in combination, a housing, a tablet magazine rotatable in said housing, said magazine being arranged to store a plurality of tablets disposed in individual units one above

20 the other and in columns arcuately positioned within the magazine and deliverable in single units at the bottom, a shelf extending into the magazine on which the tablets can slidably rotate and arranged to allow each column of tablets

25 to align consecutively therewith and release a unit therefrom individually at a time for its removal from the magazine a coin tube within the magazine for guiding said coin therethrough, a knob rotatable on the housing including a slot

30 for the insertion of the coin therein and guiding it to the magazine and bridging and keying the knob and magazine together whereby the further rotation of the knob will produce corresponding rotation in the magazine and bring each column

35 selectively to said position of release, said magazine being arranged to align itself with said tube in said position and drop the coin from its bridging position into the tube, a coin box in the housing adapted to receive the coin from said tube,

40 a delivery cup in the housing alignable also with the column in its releasing position for receiving the unit dispensed therefrom simultaneously with the dropping of the coin, and means for returning the knob to its normal position on

45 the housing ready for the next coin to be inserted, without moving said magazine during said return, a plate in the housing on which the magazine rests including an opening therein for the unit to drop through, means operating in the

50 housing adjacent said shelf for leaving the opening through which the unit may fall to the cup open as long as there are tablet units in the magazine to press it open, and a diverter mounted in the housing hinged in said coin tube and including means actuated by said last mentioned

55 means when all the tablet units have been emptied from the magazine to guide the coin inserted in the housing to said cup.

3. A dispensing machine operable by coin manipulation, comprising in combination, a housing, a tablet magazine rotatable in said housing, said magazine being arranged to store a plurality of tablets disposed in individual units one above

60 the other and in columns arcuately positioned within the magazine and deliverable in single units at the bottom, a shelf extending into the magazine on which the tablets can slidably rotate and arranged to allow each column of tablets to

65 align consecutively therewith and release a unit therefrom individually at a time for its removal from the magazine, a coin tube within the magazine for guiding said coin therethrough, a knob rotatable on the housing including a slot for the insertion of the coin therein and guiding it to

70 the magazine and bridging and keying the knob

and magazine together whereby the further rotation of the knob will produce corresponding rotation in the magazine and bring each column selectively to said position of release, said magazine being arranged to align itself with said tube in said position and drop the coin from its bridging position into the tube, a coin box in the housing adapted to receive the coin from said tube, a delivery cup in the housing alignable also with the column in its releasing position for receiving the unit dispensed therefrom simultaneously with the dropping of the coin, and means for returning the knob to its normal position on the housing ready for the next coin to be inserted, without moving said magazine during said return, a plate in the housing on which the magazine rests including an opening therein for the unit to drop through, means operating in the housing adjacent said shelf for leaving the opening through which the unit may fall to the cup open as long as there are tablet units in the magazine to press it open, a diverter mounted in the housing hinged in said coin tube and including means actuated by said last mentioned means when all the tablet units have been emptied from the magazine to guide the coin inserted in the housing to said cup, and a ratchet mechanism connected between the stationary coin tube and the magazine for preventing the latter from being reversed in direction.

4. A dispensing machine operable by coin manipulation, comprising in combination, a housing, a tablet magazine rotatable in said housing, said magazine being arranged to store a plurality of tablets disposed in individual units one above the other and in columns arcuately positioned within the magazine and deliverable in single units at the bottom, a shelf extending into the magazine on which the tablets can slidably rotate and arranged to allow each column of tablets to align consecutively therewith and release a unit therefrom individually at a time for its removal from the magazine, a coin tube within the magazine for guiding said coin therethrough, a knob rotatable on the housing including a slot for the insertion of the coin therein and guiding it to the magazine and bridging and keying the knob and magazine together whereby the further rotation of the knob will produce corresponding rotation in the magazine and bring each column selectively to said position of release, said magazine being arranged to align itself with said tube in said position and drop the coin from its bridging position into the tube, a coin box in the housing adapted to receive the coin from said tube, a delivery cup in the housing alignable also with the column in its releasing position for receiving the unit dispensed therefrom simultaneously with the dropping of the coin, and means for returning the knob to its normal position on the housing ready for the next coin to be inserted, without moving said magazine during said return, a plate in the housing on which the magazine rests including an opening therein for the unit to drop through, means operating in the housing adjacent said shelf for leaving the opening through which the unit may fall to the cup open as long as there are tablet units in the magazine to press it open, a diverter mounted in the housing hinged in said coin tube and including means actuated by said last mentioned means when all the tablet units have been emptied from the magazine to guide the coin inserted in the housing to said cup, a ratchet mechanism connected between the

5 the stationary coin tube and the magazine for preventing the latter from being reversed in direction, and a section of the housing adapted for closing in the money box, and means for locking the box in said section.

5. A dispensing machine operable by coin manipulation, comprising in combination, a housing, a tablet magazine rotatable in said housing, said magazine being arranged to store a plurality of tablets disposed in individual units one above the other and in columns arcuately positioned within the magazine and deliverable in single units at the bottom, a shelf extending into the magazine on which the tablets can slidably rotate and arranged to allow each column of tablets to align consecutively therewith and release a unit therefrom individually at a time for its removal from the magazine, a coin tube within the magazine for guiding said coin therethrough, a knob rotatable on the housing including a slot for the insertion of the coin therein and guiding it to the magazine and bridging and keying the knob and magazine together whereby the further rotation of the knob will produce corresponding rotation in the magazine and bring each column selectively to said position of release, said magazine being arranged to align itself with said tube in said position and drop the coin from its bridging position into the tube, a coin box in the housing adapted to receive the coin from said tube, a delivery cup in the housing alignable also with the column in its releasing position for receiving the unit dispensed therefrom simultaneously with the dropping of the coin, and means for returning the knob to its normal position on the housing ready for the next coin to be inserted, without moving said magazine during said return, a plate in the housing on which the magazine rests including an opening therein for the unit to drop through, means operating in the housing adjacent said shelf for leaving the opening through which the unit may fall to the cup open as long as there are tablet units in the magazine to press it open, a diverter mounted in the housing hinged in said coin tube and including means actuated by said last mentioned means when all the tablet units have been emptied from the magazine to guide the coin inserted in the housing to said cup, a ratchet mechanism connected between the stationary coin tube and the magazine for preventing the latter from being reversed in direction, a section of the housing adapted for closing in the money box, and means for locking the box in said section, said housing being in plural sections for enabling its upper, bottom and middle sections to be detached from each other and attaining access to the magazine and mechanisms within it for inspection, repair and replacement purposes.
